MAGNETIC TAPE REEL CASE

James E. Harris, Auburn, Ala., assignor to Ampex
Corporation, Redwood City, Calif.

Filed June 19, 1970, Ser. No. 23,569

Term of patent 14 years

Int. Cl. D3—99

U.S. Cl. D87—1

FIG. 1 is a perspective view of the front, top and right side of a magnetic tape reel case showing my new design;

FIG. 2 is a perspective view thereof of the back, top, and left side; and

FIG. 3 is a bottom plan view thereof.

I claim:

The ornamental design for a magnetic tape reel case, substantially as shown.
